(57) **CLAIM**

The ornamental design for a scissor, as shown and described.

DESCRIPTION

FIG. 1 is a perspective view showing my new design of a scissor;

FIG. 2 is an exploded perspective view thereof;

FIG. 3 is a top plan view thereof;

FIG. 4 is a bottom plan view thereof;

FIG. 5 is a right side elevational view thereof;

FIG. 6 is a left side elevational thereof;

FIG. 7 is a bottom elevational view thereof;

FIG. 8 is a top elevational view thereof;

FIG. 9 is a perspective view of a left lever cover of the scissor of FIG. 1;

FIG. 10 is a perspective view of a right lever cover of the scissor of FIG. 1;

FIG. 11 is a bottom perspective view of a left blade cover of the scissor of FIG. 1;

FIG. 12 is a top perspective view of a left blade cover of the scissor of FIG. 1;

FIG. 13 is a top perspective view of a right blade cover of the scissor of FIG. 1; and,

FIG. 14 is a bottom perspective view of a right blade cover of the scissor of FIG. 1.

The broken lines of a cable in FIGS. 1 to 5 are for the purpose of illustrating unclaimed environment of the design, are for illustrative purposes only, and form no part of the claimed design.

The dash-double-dash lines in FIG. 2 are only present to show connectivity of the parts of the claimed design when separated from one another and form no part of the claim.

1 Claim, 5 Drawing Sheets
